US0D1049392S

(12) **United States Design Patent** (10) **Patent No.:** **US D1,049,392 S**
(45) **Date of Patent:** **** Oct. 29, 2024**

(54) **ADHESIVE BANDAGE WITH DECORATED PAD**

(71) Applicant: **Johnson & Johnson Consumer Inc.**, Skillman, NJ (US)

(72) Inventors: **Leonardo Canepele**, São José dos Campos (BR); **Andre Narcizo**, São José dos Campos (BR); **Paulo Cesar de Godoy Oriani**, São José dos Campos (BR); **Carmine Rizzo**, Port St. Lucie, FL (US); **Andre Luiz Santos**, São José dos Campos (BR)

(73) Assignee: **Johnson & Johnson Consumer Inc.**, Skillman, NJ (US)

(**) Term: **15 Years**

(21) Appl. No.: **29/776,231**

(22) Filed: **Mar. 29, 2021**

Primary Examiner — Jennifer L Watkins

CLAIM

The ornamental design for an adhesive bandage with decorated pad as shown and described.

DESCRIPTION

FIG. 1 is a top perspective view of an adhesive bandage with decorated pad;

FIG. 2 is a top view of the adhesive bandage with decorated pad depicted in FIG. 1;

FIG. 3 is a left side view of the adhesive bandage with decorated pad depicted in FIG. 1;

FIG. 4 is a bottom view of the adhesive bandage with decorated pad depicted in FIG. 1;

FIG. 5 is a right side view of the adhesive bandage with decorated pad depicted in FIG. 1;

FIG. 6 is a front side view of the adhesive bandage with decorated pad depicted in FIG. 1; and,

FIG. 7 is a back side view of the adhesive bandage with decorated pad depicted in FIG. 1.

The dashed lines in the drawings depict portions of an adhesive bandage with decorated pad and form no part of the claim.
